UNITED STATES PATENT OFFICE.

THOMAS H. GRAYDON, OF CINCINNATI, OHIO.

ARCH-SUPPORTING SHOE.

1,236,424.

Specification of Letters Patent. Patented Aug. 14, 1917.

Application filed December 17, 1915. Serial No. 67,345.

To all whom it may concern:

Be it known that I, THOMAS H. GRAYDON, a citizen of the United States, and a resident of the city of Cincinnati, in the county of 5 Hamilton and State of Ohio, have invented certain new and useful Improvements in Arch-Supporting Shoes, of which the following is a full, clear, and exact description, reference being had to the accompanying 10 drawing, forming part of this specification.

My invention relates to shoes which provide a means for supporting the arch of the foot. In devices of this character, there are a variety of shoes made up with reinforcing 15 counters, metallic reinforcing means and the like, which bear on the arch portions of the foot. In these shoes when the counters or reinforcements break down, which they are bound to do after wear, then the arch is left 20 without the extra support. There is no means of taking up the wear of this reinforcement, and it is stiff at first, and worn down later.

It is the object of my invention to build 25 into the shoe an instep bandage, and tie it to the sole of the shoe so that the arch will be held up by the shoe sole, and the whole shoe act in conjunction with the arch support. It is also my object to use this bandage 30 device in connection with stiffening or reinforcing devices when desired, said bandage keeping up the life of the stiffeners. It is also the object to have this bandage concealed from view and capable of being taken 35 up as the leather of the shoe stretches and the sole becomes worn and soft, and furthermore to arrange the laces of the shoe so that they will act as the laces for the bandage.

These objects I accomplish by that certain 40 construction and arrangement of parts to be hereinafter more specifically pointed out and claimed.

In the drawing,

Figure 1 is a side elevation of a shoe 45 partly broken away.

Fig. 2 is a vertical section through the instep bandage.

Fig. 3 is a top plan view of a low shoe with the bandage exterior to the shoe.

50 Fig. 4 is a bottom plan, Fig. 5 a left side elevation, and Fig. 6 a right side elevation of a last having counters tacked thereto.

Fig. 7 is a left side elevation of the same parts with the addition of the bandage.

55 Fig. 8 is a right side elevation of the parts shown in Fig. 7.

1 is the sole of the shoe and 2 the upper thereof. The upper has eyelets 3, 3, through which the usual laces 8 are drawn in the customary manner to draw the parts of the 60 upper together over the foot.

In making up the shoe, the upper is drawn over a last and together with the upper and inside of it in my preferred form are drawn the flexible members 4, 4, of the 65 instep bandage. As shown in Fig. 2, the upper and bandage portions are then inseamed to the lip of the insole 5 together with the welt 6, and the welt then stitched onto the outer sole 1. If it is desired to have 70 the flexible bandage members outside of the upper so as to show in the completed shoe, which would probably be done with athletic shoes (Fig. 3), then the said members are secured to the insole on the outside of the 75 upper.

The flexible members have eyelets 7, 7, which receive the laces 8 of the shoe proper. The lacing is done by merely bringing the lace after passing through an eyelet of the 80 shoe upper, out and through the eyelet of the flexible member. It is then brought over and through the opposite eyelet of the upper and then out and through the opposite bandage member. In this way, the strain of the 85 laces is borne by the bandage and the tightening of the laces will draw up the bandage without materially affecting the lacing of the upper. Not only this, but this interior lacing does not show to the eye, and 90 to outer appearance there is nothing unsightly or out of the ordinary about the shoe.

It is also desirable to have suitable counters in connection with new bandages, as 95 these counters are of great value in giving the proper bearing surface for the sides of the arch of the foot, and as their use in conjunction with the adjustable bandage results in a shoe which will always adequately 100 support and give contour to the arch. As heretofore stated, the counters, if put into an ordinary shoe, are dependent on the sole of the shoe for keeping them in proper shape and position. A shoe sole will wear down 105 and become soft in a very short time, and then the counter wears also and stretches out of shape and out of the proper position to give shape to and support the arch. With the sole held up at the point of strain 110 in a flat footed person by the bandage which can be tightened after the shoe is worn soft,

these counters will remain in proper condition, and be of permanent value as long as the shoe lasts.

The counters are set in the usual way. I 5 prefer to have a long counter 9 on the outside of the shoe, the same extending around the heel and along the inside of the shoe at 10. Then directly under the arch is placed another counter 11, both of said counters 10 being inseamed into the shoe together with the welt, as is customary for welted shoes.

It should be understood that I do not limit myself to welted shoes, as in other species of shoes this bandage could be used by 15 securing it in some other manner. Furthermore I do not wish limitations to be implied in the claims that follow, where the wording is not specific, so as to exclude from their scope the range of equivalent structures, 20 either from my failure to mention such equivalents, or from my failure at this time to fully appreciate the usefulness of my invention.

Having thus described my invention, what 25 I claim as new and desire to secure by Letters Patent, is:—

1. In an arch supporting shoe, the combination with a sole for the shoe and an upper having eyelets and lacing, of a pair of 30 flexible pieces for supporting the foot, and

means for securing said pieces, one on each side of the sole of the shoe at the shank portion thereof, said pieces extending up toward the instep of the foot, and having eyelets to receive the laces of the shoe, said eyelets being located so as to come below the eyelets in the upper whereby the tension of the pieces may be adjusted by tightening or loosening the lacing of the shoe.

2. In an arch supporting shoe, the combination with a sole for the shoe and an upper having eyelets and lacing, of a pair of flexible pieces for supporting the foot, and means for securing said pieces, one on each side of the sole of the shoe at the shank 45 portion thereof, said pieces extending up toward the instep of the foot, and having eyelets to receive the laces of the shoe, said eyelets being located so as to come below the eyelets in the upper whereby the tension 50 of the pieces may be adjusted by tightening or loosening the lacing of the shoe, and the sole of said shoe having arch supporting stiffeners incorporated therewith at the shank portion, whereby the tensioning of 55 the flexible pieces will pull upwardly and forwardly toward the instep the arch supporting stiffeners.

THOMAS H. GRAYDON.
